FLUORESCENT LIGHTING FIXTURE

Pasquale J. Lepore, Somerville, Mass., assignor to
Sylvania Electric Products Inc., Salem, Mass.,
a corporation of Massachusetts

Application September 12, 1947, Serial No. 141,356

Term of patent 14 years

(Cl. D48—4)

To all whom it may concern:

Be it known that I, Pasquale J. Lepore, a citizen of the United States, residing at Somerville, in the county of Middlesex and State of Massachusetts, have invented a new, original, and ornamental Design for a Fluorescent Lighting Fixture, of which the following is a specification, reference being had to the accompanying drawing, forming part hereof.

In the drawing:

Figure 1 is a front perspective view of a fluorescent lighting fixture showing my new design.

Figure 2 is a top plan view thereof, and
Figure 3 is a side elevational view.

The dotted lines shown in the drawing are for illustrative purposes only.

I claim:

The ornamental design for a fluorescent lighting fixture, as shown and described.

PASQUALE J. LEPORE.
